LUMINOUS NUMBER PLATE AND OTHER
LUMINOUS SIGNS

William Coleraine McKnight, Glasgow, Scotland

Application October 26, 1936, Serial No. 107,713
In Great Britain September 30, 1935

1 Claim. (Cl. 40—133)

This invention relates to luminous number plates and other luminous signs provided with letters, numerals and/or other configurations. The invention is especially applicable to number plates for motor vehicles but is not confined to such application, being applicable to luminous signs in general.

An object of the invention is to provide a sign enclosing a source of light and having a face 10 provided with strips constituting configurations which are perforated with holes through which the light shines. Another object of the invention is to provide holes as aforesaid which are so small that mud is more or less completely prevented from entering the sign and fouling its interior and that the legibility of the configurations in daylight is not affected. Another object of the invention is to arrange the holes in close spacing along the margins of the strips to ensure 15 that the holes produce sharply delineated luminous symbols which approximate closely to the shapes of the respective configurations and which are clearly visible in darkness at a reasonable distance. Yet another object of the invention 20 is to countersink the holes at the back of the face so that the rays of light passing to and through the holes are concentrated and in addition the holes are rendered more suitable for cleaning.

As applied to the number plates of motor vehicles, the sign is fronted by a single face plate 30 having the perforated configurations, the plate being of standard form and being a sliding fit in a supporting hollow structure. By "standard form" is meant the long rectangular form 35 customarily given to the number plates of motor vehicles.

An advantage of a sign according to the invention is that the face, including the symbols thereon, can be composed wholly of metal or wood or 40 other relatively strong opaque material, need for glass or other transparent or translucent material being entirely obviated.

The invention will now be described by way of example with reference to the accompanying drawing, in which a number-plate structure embodying the invention is illustrated.

Fig. 1 of the drawing is an elevation of the entire structure.

Fig. 2 is a vertical cross section, Fig. 3 a section 50 viewed in the same direction as Fig. 1 and Fig. 4 a plan, partly in section, of the structure with the number plate proper removed.

Fig. 5 is a vertical section, drawn to a larger scale, of the number plate, showing holes through 55 one of the configurations provided thereon.

The number plate shown is of standard form, consisting of a metal face plate 10 to which are secured (by riveting, welding or otherwise) strip-form metal letters 11 and numerals 12. The face plate 10 is or may be blackened or dark-coloured (by enamelling or otherwise) and the configurations 11, 12 are or may be light-coloured (also by enamelling or otherwise, or by making them of a whitish-coloured metal—such as aluminium or of an electro-plated metal). A multiplicity 10 of holes 13 are drilled through the configurations and face plate, these holes as shown being spaced closely together and arranged marginally, in two lines, round the strips forming the configurations to delineate the shapes thereof. The holes 13 15 are very small, holes of about one-sixteenth or three thirty-seconds of an inch in diameter having been found satisfactory, and holes of such a size I regard as being most advantageous, although slightly differently sized holes could be 20 made. Moreover, the holes are counter-sunk at the back of the plate; and the counter-sinking may extend throughout the entire depth of the holes.

The number plate structure comprises a hollow metal container which is closed on top, at the bottom, at both sides and at the rear leaving an open front adapted to receive the number plate. The open front is bounded by upper and lower grooved portions 14, 15 in which the plate 30 10 is a sliding fit, by an end grooved portion 16 in which the adjacent end of the plate 10 fits when the plate is slid fully home, and by a detachable grooved part 17 which is attachable by nuts 18 to the structure in order to lock the plate 35 10 in place. Thus the number plate can be readily slid into and locked in place at the front of the structure and can be removed at will.

The top 19 of the number plate structure is provided internally of the structure with several 40 holders 20 for electric-light bulbs 21, a cable for the supply of electricity being denoted by 22.

The rear 23 of the number plate structure may be enamelled white, or it may be polished, so as to reflect light as brightly as practicable towards the holes 13 with which the number plate is perforated.

In the drawing, no provision has been shown for attaching the structure to the vehicle; but it will be readily understood that any suitable 50 brackets or other attachment devices may be provided on the structure according to requirements, or provision may be made for attaching the rear 23 by screws or otherwise to a bracket or other fixture on the vehicle.

Preferably, in the interests of compactness, where the structure is intended for use as a rear number plate, the structure is provided on top with a holder (not shown) for the usual rear electric light bulb, the cable 22 being electrically connected to such a holder.

The cable 22 has been shown broken-off at the exterior of the structure, but it will be clear that the cable would form part of the ordinary electric lighting system of the vehicle, or could be adapted 10 for convenient connection to said system.

In use of the number plate structure, when the lights 21 are "on", the interior of the structure is brightly illuminated, with the result that in 15 darkness the holes 13 shine brightly as spots of light disposed throughout areas of much the same shapes as the symbols 11, 12 themselves, so that in effect clearly visible symbols are produced.

Various modifications of a constructional 20 nature may be made without departing from the scope of the claim hereinafter set forth. For example, the rear wall of the structure may be so inclined and the source of light so arranged that rays of light therefrom are reflected directly 25 through the holes with which the configurations are perforated roughly in the direction in which the luminous symbols would ordinarily be viewed. Further, instead of providing several electric

bulbs a single tube (such as a neon tube) could be provided, so that the light would be more uniformly diffused and distributed behind the configurations. The light may be white or of any other suitable colour. The configurations need not be 5 made separately from the face plate, but may be integral parts thereof, it being simply requisite that the strips forming them stand distinctly in relief against the back-ground portions of the plate; for example, the configurations may be 10 formed by embossing or pressing-out strips on the plate.

I claim—

An illuminated sign for vehicles comprising 15 a casing having a light reflecting back wall and a front wall having an opening adapted to receive a license number plate, indicia bearing elements on said plate having small closely spaced apertures extending along the marginal edges of the indicia, corresponding apertures in the number plate flaring inwardly from the holes in the indicia, a source of light in said casing adapted to be reflected from the back wall to the flared openings in the plate to concentrate the rays 20 through the indicia openings and emit therefrom 25 well defined configurations of the indicia.

WILLIAM COLERAINE MCKNIGHT.
